UNITED STATES PATENT OFFICE.

FRANK LORENZ MARY, OF CHEHALIS, WASHINGTON.

CRATE.

No. 890,525.

Specification of Letters Patent.

Patented June 9, 1908.

Application filed March 14, 1907. Serial No. 362,299.

To all whom it may concern:

Be it known that I, FRANK LORENZ MARY, a citizen of the United States, and a resident of Chehalis, in the county of Lewis and State 5 of Washington, have invented a new and useful Improvement in Crates, of which the following is a full, clear, and exact description.

The purpose of the invention is to provide a simple, durable and economic crate especially adapted for shipment of poultry, but it 10 may be used for other purposes, and to so construct the crate that it can be quickly and conveniently folded flat so as to occupy but little room and be locked in folded position, 15 and so that further, the crate can be as conveniently and quickly set up for use.

It is also the purpose of the invention to so construct a folding crate that none of the parts is separated from the body of the crate, 20 while being knocked down or set up, so that no portion of the crate is liable to be lost or misplaced.

The invention consists in the novel construction and combination of the several 25 parts as will be hereinafter fully set forth and pointed out in the claims.

Reference is to be had to the accompanying drawings forming a part of this specification, in which similar characters of reference 30 indicate corresponding parts in all the figures.

Figure 1 is a perspective view of the improved crate set up, a portion of the top being shown open, the view being drawn upon a 35 small scale; Fig. 2 is a transverse section through the crate drawn upon a larger scale, the section being taken practically on the line 2—2 of Fig. 3, the crate being shown set up for use, and one of the side sections folded 40 up against the top and the opposing side section in sustaining position; Fig. 3 is a longitudinal section taken substantially on the line 3—3 of Fig. 2; Fig. 4 is a longitudinal section through the crate folded; Fig. 5 is a detail 45 partial transverse section showing the manner in which the crate is locked in folded position; and Fig. 6 is a detail perspective view of a portion of the inside of the crate showing how the sides are held in proper position 50 when the crate is set up.

The crate consists of a top section A, a bottom section B, end sections C, and side sections D. Relatively to the top section A it consists in detail of end members 10 and side

members 11, and cross bars 12 that extend 55 from one side member to the other at each side of the center of the top section forming thereby an intervening space 14^a between the said bars 12 and the space between the bars 12 and the end members 10 of the top section 60 is filled in by a reticulated or perforated material 13, preferably a wire netting of suitable mesh. A slide 14 is made to practically close the aforesaid opening 14^a and this slide is made to operate beneath strips 15 attached 65 to the upper portion of the top section A and spanning the opening 14^a at its ends, while upper and lower guide strips 16 span the said opening 14^a at its central portion. See Fig. 1.

Preferably the sliding section 14 of the 70 cover or top section of the crate is separated from the strips 12, as is illustrated in Figs. 2 and 3, and in order that the said sliding section 14 of the top section may have guided movement in closing or unclosing the opening 75 14^a, projections 17 usually in the nature of pins are carried down from the bridging or spanning strips 15 and 16, as is shown in Figs. 3 and 4, but I desire it to be understood that the slide 14 may fit closely to the transverse 80 strips 12 at the central portion of the top section A of the crate.

Blocks 18 are secured to the inner faces of the side members 11 of the top, one at each side of the center of the said member, as is 85 shown in Figs. 3 and 4, and pivot rods 19 are loosely passed through the blocks 18, which pivot rods are supports for the side sections D of the crate. Each side section D of a crate consists of horizontal upper bars 20 and 90 horizontal lower bars 21 connected by end upright bars 22 and a central upright bar 23 which extends at its upper end between the blocks 18, but I do not limit myself to the number of horizontal bars 20 or upright or 95 vertical bars 22 and 23, but the horizontal bars 20 and 21 receive between them a wire mesh 24, the mesh being secured to the said bars in any suitable or approved manner, and the upright or vertical bars 22 and 23 are 100 located at the inner faces of the said side sections D and extend above and below the horizontal bars 20 and 21. The pivot rods 19 are passed through the upper end portions of the vertical connecting bars 22 and 23, as is 105 shown in Fig. 3, and the said pivot rods 19 extend out through the end members 10 of the top section A of the crate, being provided

at their outer ends with suitable nuts. It may be here stated that in each side member 11 of the top section A, a longitudinal slot 11^a is produced extending from a point 5 near each end and terminating at a point near the center of the side member 11 in which the slot is produced.

The bottom section B consists of a bottom member 25, side members 26 that extend in an 10 upwardly direction, and end members 27. The bottom section B corresponds in shape and dimensions to the top section A. The bottom section B at its central portion is provided with a transverse beam 29 secured to 15 the upper face of its lower member 25, and on this beam 29 at each end, an angular latch 30 is mounted to turn in guides 31 and 32 secured to the said bars 29, as is shown in Fig. 6.

The side sections D are pivoted by means 20 of the rods 19 to the blocks 18 and the end members 10 of the top section A, as has been described, and when these side sections are in their vertical or sustaining positions shown to the right in Fig. 2, and in Figs. 1 and 3, 25 they are so held by means of the said latches 30, which are made to engage with the central upright bars 23 of the side sections, but when the crate is to be folded or knocked down the latches 30 are turned so as to free 30 them from the aforesaid side sections D and permit the said side sections to be folded up closely beneath the top section A, as is shown to the left in Fig. 2, and is also shown in Fig. 4.

35 The end sections C consist of upper parallel twin bars 33 corresponding to the upper bars 20 of the side sections D, and lower parallel or twin bars 34 corresponding to the bars 21 of the side sections and connecting 40 bars 35 located vertically at the end portions of the said sections, as is shown in Fig. 2, the end vertical bars 35 extending respectively above and below the twin bars 33 and 34 which are horizontal bars and a wire mesh 36 45 is suitably held between the parallel or twin bars 33 and 34. Pivot rods 37 extend through the upper ends of the vertical end members 35 of the end sections C and out through the slots 11^a in the side members of 50 the top section A of the crate and parallel lower pivot bars 38 are made to extend through the lower ends of the end members 35 of the end sections C and out through the side members 26 of the bottom section B so 55 that the end sections C are pivotally connected with the bottom B and are pivotally and slidably connected with the top section A. The outer ends of the pivot rods 37 and 38 of the end sections C are connected at the front 60 and at the rear of the crate by links 39.

The latch 40 is secured to the front central portion of the top section A of the crate, the said latch being provided with an opening 41 adjacent to its lower end and when the crate 65 is folded, the lower end of the latch 40 passes

through a keeper 42 occupying a corresponding position relatively to the lower section B and the opening 41 therein receives a slight pin-like projection 43 from the said lower section B, as is clearly shown in Fig. 5. 70 When the crate is set up the latches 30 locking the side section B insures the stability of the structure and the slide 14 can be opened or closed readily as occasion may demand.

When the crate is empty and is to be folded 75 up it is simply necessary to open the slide 14, turn the bolts 30 from engagement with the side sections D, and to fold the said side sections up closely beneath the under face of the top section A, as is shown in Fig. 4, and then to force the top section A down to an engagement with the bottom section B, during 80 which action the end sections C will by reason of their peculiar mounting be carried inward and downward occupying the position shown in Fig. 4, and as the top section A meets the bottom section B the two sections are locked together in the manner which has been described.

When the crate is to be set up for use it is 85 simply necessary to disengage the latch 40 from its keeper, raise the top section, whereupon the side sections will drop to their vertical or sustaining positions, and the end sections will automatically be brought to their 90 sustaining or upright positions, finally, the latches 30 are brought to engage with the side sections D insuring the stability of the structure, as has been described.

I desire it to be understood that the folding 95 construction described relatively to a crate, is equally adaptable to boxes and like receptacles.

Having thus described my invention, I 100 claim as new and desire to secure by Letters 105 Patent,—

1. A folding crate or like receptacle comprising a top and a bottom section, opposing intermediate sections mounted to fold upward and inward, other opposing intermediate sections, upper and lower pivot rods for the last mentioned sections, the lower pivot rods being pivotally connected with the bottom section and the upper pivot rods having sliding connection with the top section 115 whereby the said intermediate sections may be folded inward and downward, and links connecting the said upper and lower pivot rods.

2. A folding crate or like receptacle, comprising a top and a bottom section, opposing intermediate sections having upright members at the ends and at the center, the upright members extending at their ends within the top and bottom sections, pivot rods extending through the upper ends of said upright members and pivotally connecting the same with the top section, the said intermediate sections being free at their lower ends, and arranged to fold inward and upward, a 120 125 130

transverse bar secured to the inner face of the bottom section, latches mounted to turn at the ends of said transverse bar and adapted to engage the inner faces of the said central upright members of the intermediate sections, and other opposing intermediate sections mounted to fold inward and downward, and each having a pivotal connection with the bottom section and a sliding connection with the top section.

3. A folding crate or like receptacle comprising a top and a bottom section, opposing intermediate sections mounted to fold inward, other opposing intermediate sections, upper and lower pivot rods for connecting each of the last mentioned sections with the top and bottom sections, and extending out through the side members of said top and bottom sections, and links connecting the projecting ends of said upper and lower pivot rods.

4. In a folding crate, a top section, a bottom section, side sections pivotally connected with the top section, being free at their lower ends, end sections pivotally connected at their lower ends with the bottom section and slidably and pivotally connected at their upper ends with the upper section, links connecting the upper and lower pivots of the end sections locking devices for the side sections located within the crate and exteriorly located locking means for securing the crate in folded position.

5. In a folding crate or like receptacle, a top section, a bottom section, side sections pivotally connected with the top section and free at their lower ends, end sections pivotally connected at their lower ends with the bottom section and slidably and pivotally connected at their upper ends with the top section, a transverse bar secured to the upper face of the bottom section near the central portion thereof, the said side sections having central upright bars extending at their lower ends adjacent to the transverse bar, an angular latch at each end of said transverse bar and mounted to turn in guides secured to said bar, the said latches being adapted to engage the inner faces of the said central upright bars to hold the side sections in vertical position, and locking means for securing the crate in folded position.

6. In a folding crate or like receptacle, a top, a bottom, and side and end sections, the side sections being pivoted to the top section, upper and lower pivot rods for the end sections, the lower pivot rods extending out through the sides of the bottom section, and the upper pivot rods extending out through slots in the sides of the top section, and links connecting the projecting ends of the upper and lower pivot rods of each end section.

7. A folding crate or like receptacle comprising a top section having side and end members, a bottom section also having side

and end members, side sections, rods for pivoting the upper ends of said side sections to the top section, the pivot rods extending through the end members of the top section, the side sections being free at their lower ends, end sections, rods for pivoting the lower ends of said end sections to the side members of the bottom section of the crate, pivot rods for the upper ends of the end sections, the upper pivot rods extending at their ends through longitudinal slots in the side members of said top section, and links connecting the ends of said upper and lower pivot rods of each end section.

8. A folding crate or like receptacle, comprising a top, a bottom and side and end sections, the top and bottom sections having side and end members and the top section being provided with an opening, and means for closing said opening, the side sections of the crate each having upper and lower horizontal bars and upright bars connecting the same, the upright bars extending above and below the horizontal bars, pivot rods passing through the upper end portions of said upright bars, the ends of the pivot rods extending through the side members of said top section, the said end sections of the crate being also provided with upper and lower horizontal bars and upright bars connecting the same and extending above and below the said horizontal bars, lower pivot rods passing through the lower projecting ends of said upright bars and through the side members of the bottom section of the crate, upper pivot rods extending through the upper ends of said upright bars and through slots in the side members of the said top section, and links connecting the projecting ends of the said upper and lower pivot rods of the end sections.

9. A folding crate or like receptacle, comprising a top, bottom, end and side sections, the top and bottom sections having side and end members, blocks secured to the inner faces of each side member of said top section one at each side of the center of said member, the side sections of the crate each having upper and lower horizontal bars connected by end upright bars and a central upright bar, the upright bars extending above and below the horizontal bars and the upper ends of the central upright bars extending between the said blocks, pivot rods passing through the upper end portions of said upright bars and through the said blocks, the ends of the said pivot rods extending out through the end members of said top section of the crate and provided at said outer ends with nuts, the end sections of the crate being also provided with upper and lower horizontal bars and end upright bars connecting the same, pivot rods passing through the lower ends of the upright bars of said end sections and through the side members of the bottom section,

pivot rods extending through the upper ends of said upright bars and through slots in the side members of the top section, means for locking the side sections of the crate in the extended position, and means for securing the crate in folded position.

In testimony whereof I have signed my

name to this specification in the presence of two subscribing witnesses.

FRANK LORENZ MARY.
